UNITED STATES PATENT OFFICE.

WILLIAM W. BRATCHER, OF NEAR PATTONSBURG, MISSOURI.

STOCK-WATERER.

1,094,775.

Specification of Letters Patent. Patented Apr. 28, 1914.

Application filed October 23, 1912. Serial No. 727,436.

To all whom it may concern:

Be it known that I, WILLIAM W. BRATCHER, a citizen of the United States, residing near Pattonsburg, in the county of De-kalb, State of Missouri, have invented certain new and useful Improvements in Stock-Waterers; and I do hereby declare the following to be a full, clear, and exact description of the invention, such as will enable others skilled in the art to which it appertains to make and use the same.

This invention relates to stock waterers.

The object of the invention resides in the provision of a stock waterer in which the discharge of water into the drinking trough may be readily changed from a downward to an upward discharge or vice versa.

With the above and other objects in view the invention consists in the details of construction and in the arrangement and combination of parts to be hereinafter more fully described, and particularly pointed out in the appended claim.

In describing the invention in detail reference will be had to the accompanying drawings wherein like characters of reference denote corresponding parts in the several views, and in which—

Figure 1 is a side elevation of a stock waterer constructed in accordance with the invention, same being shown partly in section, and Fig. 2 a view similar to Fig. 1 showing the waterer changed so as to discharge upwardly into the drinking trough instead of downwardly.

Referring to the drawings, 10 indicates a water supply tank which discharges through a pipe 11 embedded in the ground. The tank 10 is supplied with water by means of a suitable pump not shown, said pump being connected with an extension 12 of the pipe 11 so that water may also be forced into the tank 10 by way of the pipe 11 as well as discharged from said tank by the pipe 11. The adjacent ends of the pipe 12 and pipe 11 project into a casing 13 sunk into the ground and said ends are connected together by a T-joint 14. Also connected to the joint 14 is a vertical pipe section 15 which includes a valve 16 operated by means of a lever 17. The pipe section 15 is connected at its upper end with the lower end of another vertical pipe section 17' by means of a joint 18. The upper end of the pipe section 17' is bent at an angle as at 19 and is connected to a discharge pipe 20 by means

of an elbow 21. It will be noted that the pipe section 17' is rotatable in the joint 18 and also that the elbow 21 is rotatable in the pipe section 17'. Likewise the discharge pipe 20 is rotatable in the elbow 21. The discharge end of the pipe 20 is curved laterally as at 22 and is disposed in position to discharge downwardly into a trough 23 suitably mounted upon the ground. Pivottally mounted adjacent the trough 23 is a platform 24 the free end of which is connected by a cable 25 with one end of a lever 26, which latter is pivotally mounted upon an upright 27. The end of the lever 26 remote from the cable 25 is secured by means of a rod 27' to the free end of the lever 17. Adjustably mounted upon the lever 26 between the upright 27 and the rod 27' is a weight 28 which serves to depress the end of the lever 26 remote from the platform 24 and normally hold the valve 16 in closed position.

In the operation of the waterer it will be apparent that when the stock enter the platform 24 the free end of the latter will be depressed so as to operate the lever 26 on its pivot. This operation of the lever 26, will through the medium of the rod 27' actuate the lever 17 to open the valve 16 when water will flow into the trough 23, which latter may be provided with suitable drain openings to prevent overflow and also to prevent any water remaining in the trough after the use of the latter has been dispensed with. It will of course be understood that when the animal leaves the platform 24 the valve 16 will be automatically closed.

In Fig. 2 the waterer is shown as changed, for an upward discharge through the bottom of the trough 23. In this construction of the waterer the pipe section 17' is rotated to the position shown in Fig. 2 as is likewise the pipe 20. The axial rotation of the pipe 20 will dispose the laterally curved end thereof substantially horizontal, while the axial rotation of the pipe section 17', when the elbow 21 is held against rotation will lower the outer end of the pipe 20 because of the fact that the elbow 21 rotates in an inclined plane. The discharge of water into the trough 23 in the construction shown in Fig. 2 is controlled by a float valve 30 it being understood that when this construction is employed the valve 16 is always open, the rod 25 being disconnected from the platform 24. The construction of the waterer shown in Fig. 2 is adapted for use in warm weather

when there is no danger of freezing and a continuous supply of water is desired.

What I claim is:—

In a stock waterer, the combination of a 5 watering trough, a water supply pipe embedded in the ground, a casing embedded in the ground through which said supply pipe passes transversely, a delivering pipe line disposed vertically and longitudinally of the 10 casing and connected to the supply pipe and comprising a plurality of sections the lowermost of which is provided with a valve and the uppermost rotatably mounted and having its upper end bent laterally, an elbow rotatably connected to the upper end of the 15 uppermost section of the delivering pipe line, a discharge pipe rotatably connected to the elbow and having its discharge end

curved laterally and adapted to discharge into the trough downwardly in one position 20 of the uppermost section of the delivering pipe line, elbow and discharge pipe and to be disposed horizontally with respect to the trough when said uppermost section of the delivering pipe line, elbow and discharge pipe are rotated to another position whereby connections may be secured to the discharge end of the discharge pipe to effect 25 an upward discharge through the bottom of the trough.

In testimony whereof, I affix my signature, in presence of two witnesses.

WILLIAM W. BRATCHER.
